(57) **CLAIM**

The ornamental design for a finger pad for poultry feather picking machine, as shown and described.

DESCRIPTION

FIG. 1 is a perspective view of the front face of the finger pad for poultry feather picking machine showing the new design; FIG. 2 is a perspective view of the rear face of the invented finger pad of FIG. 1;

FIG. 3 is a front view of the finger pad of FIG. 1;
FIG. 4 is a left side view of the finger pad shown in FIG. 3, the right side view being a mirror image thereof;
FIG. 5 is a top view of the finger pad of FIG. 3;
FIG. 6 is a rear view of the finger pad of FIG. 3; and,
FIG. 7 is a bottom view thereof.
